Application March 3, 1954, Serial No. 413,782

4 Claims. (Cl. 131—10)

This invention relates to cigarettes. Specifically, it relates to means for causing the smoke to travel a greater distance through the cigarette before reaching the smoker's mouth. It will be apparent that this will result in the smoke being cooler. Also, the smoke will be cleaner because it will have been more effectively filtered by its extended contact with the tobacco filler.

Specifically, the invention comprises a spiral, substantially a right helicoid in form, of a strip material placed within the cylindrical wrapper. The edges of the strip fit against the wrapper, and it therefore acts as a baffle and directs the smoke along a spiral path. A suitable material for use in this baffle is rice paper or other paper used in cigarette wrappers. Leaf tobacco may also be used.

A preferred embodiment of the invention is shown in the accompanying drawing which is an axial section of a cigarette embodying the invention. The tobacco filler has been omitted from a portion of the cigarette in the interests of clarity.

Referring now to the drawing: Numeral 1 indicates a cigarette having a tubular wrapper 2 and a tobacco filler 3. A one-piece or unitary baffle 4, formed substantially as a right helicoid, is disposed within the filler 3 and has its transverse dimension extending through the major portion of the filler. The lateral edges 5, 6 of the baffle 4 contact the wrapper 2. It will be noticed that the filler 3 is shown arranged spirally, but the invention is not limited to this arrangement.

2

The baffle 4 causes the smoke to follow a spiral course through the wrapper. As has been pointed out, this has the desirable effect of cooling and filtering the smoke more effectively than is characteristic of conventional cigarettes. The effect is obtained without increasing the cigarette's length. The material of baffle 4 must be combustible so that it is burned together with the tobacco and it must not adversely change the taste of the cigarette. Rice paper or other cigarette wrapping paper may be used. Leaf tobacco may also be used.

The drawing is illustrative only and no limitation to the number of convolutions shown is intended.

I claim:

- 15 1. A cigarette comprising a tubular wrapper; a tobacco filler therein; and a unitary baffle, substantially right helicoidal in form within said filler and having its transverse dimension extending through the major portion of the filler, the lateral edges of said baffle contacting said wrapper, and said baffle consisting of a combustible material other than said filler, the smoke from which is compatible in taste with tobacco smoke.
- 20 2. The combination defined in claim 1, in which said combustible material is rice paper.
- 25 3. The combination defined in claim 1, in which said combustible material is leaf tobacco.
- 30 4. A cigarette comprising a tubular wrapper; a tobacco filler therein; and a unitary baffle, substantially right helicoidal in form within said filler, the lateral edges of said baffle contacting said wrapper, and said baffle consisting of paper, the smoke from which is compatible in taste with tobacco smoke.
